UNITED STATES PATENT OFFICE.

JOHAN M. ANDERSEN, OF BOSTON, MASSACHUSETTS.

DESIGN FOR A BICYCLE-FRAME.

SPECIFICATION forming part of Design No. 26,522, dated January 12, 1897.

Application filed August 14, 1896. Serial No. 602,818. Term of patent 14 years.

To all whom it may concern:

Be it known that I, JOHAN M. ANDERSEN, residing in Boston, in the county of Suffolk and State of Massachusetts, have invented 5 and produced a new and original Design for a Bicycle-Frame, of which the following description, in connection with the accompanying drawing, is a specification, like letters on the drawing representing like parts.

The design relates to a bicycle-frame of that class of cycles known as "tandems;" and it consists in a bicycle-frame distinguished by its peculiar shape, as will be hereinafter set forth and claimed.

The drawing represents in side elevation a bicycle-frame embodying this design.

The leading feature of my design consists in a longitudinally-extended tube or bar a , which is fastened to the head a' of the frame and inclines downwardly for a portion of its length, and then extends horizontally beyond the first seat post or tube a^3 and to the second seat post or tube a^4 , to which latter it is secured. From the head a' also extends a downwardly-inclined bar b , joined to a hanger b' , from which extend substantially horizontal tubes or bars b^2 , connected to the hanger b^3 , from which the rear seat-post a^4 extends upwardly.

The front hanger b' is connected to the tube or bar a by a short tube or bar b^4 lying in a

plane substantially parallel with the front seat-post a^3 , which is extended upward from the tube or bar a at the rear of the junction of the tube or bar b^4 with the tube or bar a , 35 so that the front seat-post a^3 and the tube b^4 are out of line with each other, but in substantially parallel planes joined by a portion of the tube a , located in a substantially horizontal plane, whereby the first seat-post from 40 its upper end to the hanger b' has the appearance of an irregular jointed seat-post.

The front seat-post a^3 forms, with a brace tube or bar c , joining it to the tube or bar a , a substantially triangular opening d between 45 the two seat-posts.

The portion of the tube or bar a between the front seat-post a^3 and the rear seat-post a^4 is substantially parallel to the tubes or bars b^2 , connecting the hangers b^3 , and forms 50 with the said tubes and the seat-posts a^3 a^4 substantially a parallelogram.

I claim—

The design for a bicycle-frame substantially as herein shown and described. 55

In testimony whereof I have signed my name to this specification in the presence of two subscribing witnesses.

JOHAN M. ANDERSEN.

Witnesses:

JAS. H. CHURCHILL,
J. MURPHY.
